WEATHER STRIP

Vincent E. Van Fleet, Detroit, Mich.

Application October 10, 1936, Serial No. 104,921

4 Claims.

(CL. 20—69)

This invention relates to metal weather strips and sash guides for windows and especially to strips and sash guides of this type which may be used in windows in which the sashes slide within the window frame, as in the common double-hung type of window.

In designing sliding windows having wooden sashes several factors are to be considered. Provision must be made for the natural swelling and shrinking of the wood as the seasons and the weather changes, and, at the same time, leakage of air should be prevented. It is also desirable to guide the sash so that there is a minimum of wood to wood sliding contact since wood on metal forms a better bearing less liable to stick. The weather stripping should be installable with a minimum of fastenings and yet be securely held in place.

The present invention has for one of its objects the provision of a weather strip and sash guide structure fulfilling all of the above mentioned conditions and which is inexpensive to manufacture and install.

Another object of the present invention is to provide a sash guide structure for double hung windows in which all the surfaces against which the sashes rub are of metal and which comprises a plurality of similar pieces of sheet metal that can be formed in the same set of rolls.

Another object of the present invention is to provide a metal weather strip and sash guide having a minimum area of surface in contact with the sashes and having that surface arranged so as to oppose the greatest possible resistance to the infiltration of air. It has been common practice heretofore to provide longitudinal ridges on weather stripping, the tops of the ridges forming the rubbing surface, and to allow an appreciable clearance between the sash and the parting stop to lessen friction and to allow for swelling. This construction allows air to leak in alongside of the parting stop and around the edge of the sash into the space between the parting stop and the ridge on the weather strip and, having reached that space to flow up or down past the top of the bottom sash or the bottom of the top sash and thus leak into or out of the room. Attempts have been made to stop the leakage by providing cross ridges blocking the above mentioned air passages, but these cross ridges interfere with the smooth operation of the window and add considerably to the expense of forming the weather strip. Others have provided weather strip with a wide flat land extending from the parting strip to the tongue on the weather strip, but such a land unnecessarily increases friction, fails to provide proper support

for the tongue, and is too wide to indent the sash to form its own groove when the sash swells an abnormal amount. The present invention avoids these disadvantages by providing a ridge or bead alongside of the parting strip so as to form a leakage opposing contact in immediate proximity thereto without adding an appreciable amount of friction.

In the drawing,

Figure 1 is a horizontal section through one side of the upper sash and the frame, the lower sash being seen in plan.

Figure 2 is a perspective view of one end of a portion of the structure shown in Figure 1.

Figure 3 is a perspective view of one end of another portion of the structure shown in Figure 1.

Figure 4 is a view similar to Figure 1 but showing a modified form of the invention.

Figure 5 is a perspective view of one end of a portion of the weather stripping shown in Figure 3.

In the embodiment of the invention shown in Figure 1, 2 and 3, a pair of sashes 10 and 11 are slidably mounted in a window frame 12. Each sash slides in its own channel, the sides of the channel for the lower sash 10 being formed by a trim stop 15 and one side of a parting stop 14 and the sides of the channel for the upper sash 11 being formed by the other side of the parting stop 14 and a blind stop 13.

The trim stop 15 and the blind stop 13 are of wood and are secured in the conventional manner. The parting stop 14, however, is made of sheet metal and, instead of being rabbeted into the frame 12, is held against it by nails or screws.

Each of the two channels for the two sashes 10 and 11 is provided with a metal weather strip 16, 17. The strip 16 in the channel for the lower sash 10 has one edge 16a clamped between the parting stop 14 and the frame 12 and has a bead 16b with a square shoulder butting up against the side of the parting stop 14. The other edge of the strip 16 is folded back upon itself and flanged to form a projecting edge 16c, which fits under the edge of the trim stop 13, and a flange 16d, which lies against the edge of the trim stop 13. The central portion of the strip 16 is formed to provide a tongue 16e fitting into a groove 18 in the sash 10 and a bead 16f forming a bearing surface for the sash 10.

With this arrangement, the weather strip 16 is secured all along both edges by the parting stop 14 and the trim stop 15 and needs no other fastenings. The wooden sash 10 slides on metal

only, being guided on one side by the parting stop 14, on the other side by the flange 16d, and on the edge by the beads 16b and 16f.

The weather strip 17 for the outer sash 11 is 5 similar to the strip 16 for the inner sash, the two strips 16 and 17 being symmetrically placed on the two sides of the parting strip 14. This arrangement provides beads 16b and 17b for each 10 sash next to the parting strip to hinder the infiltration of air around the parting strip 14 and along the edges of the sashes 10 and 11 to the free top or bottom of the sash.

The modification shown in Figure 4 is generally similar to the one shown in Figure 1, differing 15 from it only in the construction of the parting strip 20 and the flanged edges of the weather strips 21 and 22. In this form of the invention the parting strip 20 is made of sheet metal, as in the first form, but is provided with a filling 23 made of 20 wood, impregnated paper, or other suitable material. The flanged edge of the weather strip 21 is bent out and back to form a tongue 21d of double thickness lying against the edge of the trim stop 15 and the extreme edge 21c lies in the same 25 plane as the body of the strip 21 and fits in under the trim stop 15. With this construction the metal 21d lying against the trim stop 15 is of double thickness, which makes it stronger and allows room for the accumulation of more coats 30 of paint on the exposed portion 15a of the stop 15 facing the sash 10.

Both of the constructions shown, as well as other modifications not shown, are simple and economical to produce. Each of the two pieces 35 of weather strip is the same as the other one turned end for end, so both can be produced in a single set of rolls. The metal parting strip, being of box-section, is quite rigid and can be securely held by few screws. From this, it can be 40 seen that the entire assembly is economical to produce and apply, besides providing all-metal guiding surfaces for the window sashes.

What I claim is:

1. In combination, a window frame member, a 45 pair of wooden stops secured thereto in spaced relation, a parting stop secured to the face of said frame member between said wooden stops and dividing the space between them into two channels, said parting stop having metallic side

surfaces, weather strips in each of said channels having their edges held by said stops, said weather strips being separate from said parting stop and having flanges lying against the sides of said wooden stops and shoulders fitting against the 5 sides of the parting strip.

2. In combination, a window frame member having a flat face, a stop secured against one edge of said frame member and projecting beyond the face thereof, a weather strip lying on the 10 face of said frame member with a portion fitting into a slot in said stop, said weather strip having a flange lying against the side of said stop and a shoulder spaced and facing away from said stop, a parting stop lying against said shoulder 15 and secured to the face of said frame member, a second weather strip having a shoulder fitting against the opposite side of said parting stop from said first shoulder, said second weather strip also having an upstanding flange spaced from 20 said shoulder and a portion projecting beyond said flange, and a third stop secured to said frame member and fitting over said projecting portion and against said flange.

3. In combination, a window frame member 25 having flat sides, a pair of stops each secured directly on a flat side of said frame member and forming therewith a channel for the edge of a window sash, one of said stops having a metallic surface and the other a wooden lateral surface 30 facing said metallic surface, and a metal weather strip lying in said channel, said weather strip having portions extending outwardly of said channel and covered by said stops and having a flange covering a part of said wooden lateral surface. 35

4. A sash guide comprising parallel strips of metal each having a flattened inner edge, a reversely bent portion adapted to extend in grooves formed in a window sash and a channel wall 40 comprising a reversely bent outer edge residing outwardly of said sash, and a sash parting stop comprising a separate hollow metal strip jointly overlying said inner edges; and means passing between said edges for securing said parting stop 45 directly to a window frame thereby snaring said inner edges between said stop and a window frame.
